UNITED STATES PATENT OFFICE

WILLIAM RICHTER AND PETER FRAY, OF TAMPA, FLORIDA

FIRE EXTINGUISHER

Application filed July 1, 1930. Serial No. 485,199.

Our invention relates to fire extinguishers, more particularly to fire extinguishers of the chemical type, and it consists in the constructions, combinations and arrangements herein shown and described.

It is the object of our invention to provide a fire extinguisher of the chemical type that is well adapted to put out burning fuel tanks, buildings, storage and warehouses and the like by the use of suitable chemicals adapted for this purpose.

A further object of our invention is to provide a fire extinguisher which is equipped with means for preventing inoperatives of the extinguisher from the accumulation of frost, ice, etc. at the outlets from which the chemical is sprayed, making the same especially efficient for use in cold climates.

A further object of our invention is to provide a device of the type described which has few parts, is simple to manufacture and does not get out of order easily.

Other objects and advantages will appear as the specification proceeds and the invention will be more particularly defined in the appended claim.

Our invention is illustrated in the accompanying drawing forming a part of this application, in which:

Figure 1 is a sectional view of our device;

Figure 2 is an elevational view of our device with parts thereof shown in section for the sake of illustration;

Figure 3 is an elevational detail view of a portion of the device; and

Figure 4 is a sectional detail view of the same portion of the device.

In this application of our invention we show the same utilized as a fire extinguisher for the extinction of the flame of a burning fuel storage tank 1. This fuel storage tank 1 could just as well be a house, warehouse or other object which it is desired to protect from fire.

Positioned at a distance from this object which it is desired to protect from a fire we place the operating parts 2 of my fire extinguisher, which operating parts are housed from the weather in a suitable housing 3 which as shown may be in the nature of a

penthouse. Adjacent this house we place a storage tank 4 which is adapted to store a chemical used in extinguishing fires such a chemical for instance, as carbon dioxide.

This tank 4 is suitably positioned on standards 5 and 6 for properly positioning the same while it is equipped with a chemical inlet 7 at the top thereof for the admission of chemicals thereinto.

For pumping the chemical from the tank 4 to the point of use, that is to such a point as occupied by the tank 1, we provide a pump 8 connected to said tank 4 by pipe 9 and to the place of use by a system of piping soon to be described.

This pump may be of any suitable construction, adapted to pump a fluid to put the same under pressure. It is operated by a motor 9 which may be suitably coupled thereto by a coupling 10. The motor may have a variable speed and be adapted to be thrown into and out of operation by an operator by means not shown. The shaft 11 interconnecting the pump and the motor is supported in bearings 12 and 13 on standards in the housing.

For controlling the admission of chemicals to the pump for conduction of said chemicals to the point of use, the pipe 9 is equipped with a valve 14 which valve is readily accessible for operation by an operator.

For mixing water with the chemical as it comes from the tank 4 to form a solution of said chemical in the water when desired or for applying water to the fire when the use of the chemical is not desired or the same is exhausted, we provide a conduit 15 which is connected to a source of water supply to the pipe 9 between the valve 14 thereof and the pump 8. This pipe 15 is equipped with a valve 16 which may be similar to the valve 14 for controlling the rate of flow of the water therethrough.

For conducting the chemical or water or a solution of chemicals and water to the point of use for fire extinguishing purposes we provide an outlet pipe 17 connected to the outlet of the pump and adapted to convey the fluid from said pump to other pipes for use at the desired points. This pipe is closed at its outer extremity 18 and has positioned

thereon a plurality of branch pipes 19 which branch pipes lead to chemical ejectors for ejecting the fluid onto fires at various points (not shown). These pipes 19 are equipped with valves 20 which may be similar to the valves 14 and 16 if desired. A description of one of the ejector systems at the point of use will suffice for this application.

Connected to one of these pipes 19 below the ground preferably, is a pipe 21. This pipe 21 is connected to the pipe 19 below the bend thereof. It slants upwardly from this connection and is provided with a suitable drain duct 22 at the connection for permitting an operator to drain the pipe during cold weather. It will be noted that this pipe 21 slants upwardly from the drain duct 22. A plug 22a at this point puts control of the drain in the hands of an operator.

At a desired position adjacent the point of use, this pipe 21 is bent upwardly, as shown at 23, and then bent at right angles as shown at 24, over and above the object on which it is desired to spray the chemical for extinguishing the fire. The outer extremity of this portion 24 which is adapted to be positioned immediately above the object which it is desired to protect from fire is curved as shown in Figure 1 and as indicated at 25, and provided with a number of apertures 26 from which the chemical is ejected. Each of these apertures communicates with an ejector nozzle 27 which ejector nozzle is adapted to be screwed in the aperture as indicated at 28.

The nozzles are each provided with a flat mouth 29 for spraying the chemical on the fire. It will be noted that this nozzle is of reduced cross section adjacent the mouth 29 thereof thus assuring forcible ejection of the fluid therefrom.

Tapped into the portion 23 of the pipe 21 by means of joint 30 is a circular pipe 31 provided with apertures as in the case of the bend 25 of the pipe portion 24 and equipped with nozzles for spraying fuel of similar construction to the nozzles 27. This pipe extends about the object which it is desired to protect and is secured thereto by any suitable fasteners such as the means indicated at 32. The pipe has a bend 33 therein which accommodates expansion and contraction of said pipe.

For protecting the nozzles 27 on portion 25 of pipe 21 and on pipe 31 from frost, snow and ice formations due to rain, etc., we provide a shield 34 for each of said nozzles. This shield is of semi-annular form and projects outwardly from the pipe beyond the end of the nozzle 27, thus affording efficient protection for said nozzle.

From the foregoing description, the use and operation of my device is easily understood. In the event of a fire occurring in the fuel tank or object 1, the operator simply operates the valve 14, sets the motor into op-

eration for controlling the pump 8 and operates the desired valve 20, which operations send a stream of chemical through the pipes, through the ejector nozzles 27 and onto the fire as shown most clearly in Figure 2. If it is desired to use water with the chemical he simply operates the valve 16 to the desired open position during the above described operation which valve opening dilutes the chemical with the water for spraying on the fire.

When the chemical in the tank 4 is exhausted and the operator desires to continue spraying water onto a fire he may open the valve 16 to a greater extent for securing a greater supply of water. A gage 35 positioned on the chemical tank 4 indicates to the operator the time at which the chemical is exhausted from the tank.

It is thus seen that we have provided a fire extinguisher which is adapted to spray a chemical on a fire to extinguish the same or which is adapted to spray a chemical solution on a fire as well as pure water when desired.

We claim:

In a fire extinguishing apparatus for oil tanks and like structures comprising a source of liquid supply, a main associated with said supply, pump means for forcing said liquid through said main, said main having a circular branch conduit adapted to encircle the tank in which it is wished to extinguish a fire and a conduit disposed above and over said tank, each of said conduits having nozzles to permit discharge of fluid, said liquid main being inclined downwardly from said branch conduits toward said pump, a drain plug mounted in the low end of said main, and a valve in said main disposed between the outlet of said pump and said drain plug.

WILLIAM RICHTER.
PETER FRAY.
